POPCORN MACHINE

Theodore Prisland, Evanston, Ill., assignor to C. Cretors
& Co., Chicago, Ill., a corporation of Illinois

Application August 12, 1954, Serial No. 31,847

Term of patent 14 years

(Cl. D81—10)

FIG. 1.

Fig. 1 is a front perspective view, showing my new design, and

Fig. 2 is a rear perspective view thereof.

The central top portion is plain and not indented. The stippled shading is intended to illustrate translucent material.

The other side of the popcorn machine, which is not shown, is like the side shown.

I claim:

The ornamental design for a popcorn machine, substantially as shown and described.
